(57) **CLAIM**

The ornamental design for a cervical interbody fusion device, as shown and described.

DESCRIPTION

FIG. 1 is a perspective view of a cervical interbody fusion device showing our new design;

FIG. 2 is a side view thereof;

FIG. 3 is a front view thereof;

FIG. 4 is a back view thereof;

FIG. 5 is a top view thereof; and,

FIG. 6 is a partial cross sectional view of a top or bottom portion of the device.

The stipple hatching shown depicts a porous surface.
